PNEUMATICALLY OPERATED INJECTION MOLDING INSTRUCTIONAL DEVICE

Francis Paul Pracilio, 966 Grant Ave.,
Pelham Manor, N.Y. 10803

Filed July 28, 1972, Ser. No. 276,139

Term of patent 14 years

Int. Cl. D15—09

U.S. Cl. D54—8

FIG. 1.

FIG. 2.

FIG. 3.

FIG. 1 is a perspective view of a pneumatically operated injection molding instructional device showing my new design;

FIG. 2 is a rear elevational view thereof; and

FIG. 3 is a perspective view thereof looking from the opposite side from FIG. 1.

I claim:

The ornamental design for a pneumatically operated injection molding instructional device, substantially as shown.
